UNITED STATES PATENT OFFICE

ROBERT E. SPIEL, OF CHICAGO, ILLINOIS, ASSIGNOR TO MAGILL-WEINSHEIMER COMPANY, OF CHICAGO, ILLINOIS, A CORPORATION OF ILLINOIS

DISPLAY DEVICE

Application filed December 6, 1930. Serial No. 500,490.

My invention relates to a display device and has for one purpose the provision of a display device which may include a flashing light and light pervious display members. 5 One object is the provision of such a display device adapted to be positioned upon the top of a dispensing container, slot machine or the like. Another object is the provision of means for maintaining such a device in position upon and in conformity to the form of 10 said dispensing means. Another object is the provision of a display device the light source of which is adapted also to illuminate the goods being sold as well as the display advertisement therefor. Other objects will appear from time to time in the course of the specification and claims.

I illustrate my invention more or less diagrammatically in the accompanying drawing, wherein—

Figure 1 is a perspective view illustrating my invention;

Figure 2 is a vertical section;

Figure 3 is a section on the line 3—3 of 25 Figure 2;

Figure 4 is a section on the line 4—4 of Figure 1; and

Figure 5 is a section through a variant form of the device.

Like parts are indicated by like symbols throughout the specification and drawing.

Referring to the drawing, A generally indicates a dispensing device or container, such for example as a slot machine. A¹ indicates a 35 vending window. The machine is shown as having a square or flat top A² and a vertical forward face A³.

B generally indicates an advertising display device which includes a horizontal bottom wall B¹, another horizontal bottom wall B² and a connecting bottom wall B³, perpendicular to B¹ and B² and connecting them, B¹ and B² being offset as shown in Figures 1 and 2. The wall B¹ conforms generally in shape and form to the top A² of the dispensing container and the wall B³ is shown as abutting against the front wall A³ of said container. In order to hold the display device against lateral movement in relation to the container I provide corner

angle members B¹⁵ adapted to engage the rear corners of the member A, as shown in Figures 1 and 2. It will be seen that the corner angles B¹⁵ prevent both forward and lateral movement of the display device in relation to the member B, whereas the downwardly projecting wall B⁸ prevents its rearward movement. The display device is completed by side walls B⁴, a rear wall B⁵ and inclined top wall B⁶ and a horizontal top 55 wall portion B⁷. The forward open face is bounded at top and bottom and one side by the channels B⁸. On the opposite side the top and bottom channels B⁸ are connected by the flat strip B⁹. B¹⁰ are intermediate 60 channels, dividing the front of the display device, in the form herein shown, into two parts. It will be understood that display transparencies may be inserted in said channels, as shown in the drawing. I illustrate 65 for example two separate transparencies B¹¹ and B¹².

In the form of my device shown I employ a flasher light C mounted in the socket C¹ with the conductive connections C². Any 75 suitable means may be employed for providing a flashing or intermittent light. The display members B¹¹ and B¹² are preferably formed with a forward design and a rearward or interior design. The forward design shows at all times and the rear or interior design shows only when the light is illuminated. Thus the forward picture may be modified intermittently by causing the rear picture to show therethrough. The 80 particular details of obtaining this effect do not of themselves form part of the present invention and are therefore not described in detail. In order to prevent strain on the socket C¹ I may pass a conductive connection C² through an aperture in one of the side walls B⁴, an abutment C³ being fixed on the conductive connection in order to prevent it from being pulled outwardly through 85 the aperture. As will be seen in Figure 4 the abutment C³ is of greater size than the sleeve C⁴ through which the conductive connection passes, and hence a pull on the exterior portion of the conductor or cord C² 90

100

will not tend to displace or strain the socket C¹.

For ventilating purposes, in order to prevent overheating, I may provide any suitable ventilating apertures C⁵. For example they may be in the side walls B⁴, as shown in Figures 1 and 2. I have illustrated a closure B² at the bottom of the forward portion of the display housing B. This closure may 10 be of metal or similar opaque material, but if desired it may be made of a transparent or translucent material, in order that the light from the light source C may show or flash downwardly against and through the 15 display window A¹, in order to illuminate the goods actually being dispensed.

The same effect is obtained, in possibly a heightened degree, in the variant form of my device shown in Figure 5 in which a 20 housing D is formed integrally with the top of the dispensing container or housing A. Within the housing D I may employ a mirror D¹. Another mirror D² may be positioned within the lower display member B¹². 25 Thus the light from the light source C will show downwardly into the interior of the container A. The mirror D¹ tends to throw its light forwardly and downwardly toward the display members B¹¹ B¹², while the mirror D² deflects some of its light upwardly 30 thereagainst.

It will be understood that whereas I have described and shown a practical and operative device that nevertheless many changes 35 may be made in size, shape, number and disposition of parts. I wish my drawing and description, therefore, to be taken as in a broad sense illustrative and diagrammatic, rather than as limiting me to the precise 40 structure herein shown.

I claim:

1. The combination with a dispensing member of a display device superposed upon an upper portion thereof, said display device including a portion resting upon said dispensing member and a portion forwardly extending from the dispensing member and overlapping the front thereof, the forward face of said display device including a 45 light pervious member and a light source positioned within said display device adapted to illuminate said pervious member, and securing means downwardly depending from said display device adapted to engage the sides of the dispensing member other than that engaged by the overlapping front of the display device, and to prevent lateral movement of the display device in relation to the dispensing member.

60 2. The combination with a dispensing member of a display device superposed upon an upper portion thereof, said display device including a portion resting upon said dispensing member and a portion forwardly extending from the dispensing member and over-

lapping the front thereof, the forward face of said display device including a light pervious member and a light source positioned within said display device adapted to illuminate said pervious member, and securing 70 means downwardly depending from said display device adapted to engage the sides of the dispensing member other than that engaged by the overlapping front of the display device, and to prevent lateral movement 75 of the display device in relation to the dispensing member, the display device being freely removable, upwardly, from the dispensing member.

3. The combination with a dispensing member of a display device superposed upon an upper portion thereof, said display device including a portion resting upon said dispensing member and a portion forwardly 80 extending from the dispensing member and overlapping the front thereof, the forward face of said display device including a light pervious member and a light source positioned within said display device adapted to illuminate said pervious member, and a light pervious bottom for the overlapping portion of the display device adapted to illuminate 85 the forward face of the dispensing member.

4. The combination with an upstanding housing of a display device superposed upon an upper portion of the housing, said display device including a portion resting upon said housing member and a portion forwardly extending from the housing member and downwardly extending and partially overlapping the front thereof, the forward face of said display device including a light pervious member and a light source positioned within said display device adapted to illuminate 90 said pervious member, and a light pervious bottom for the overlapping portion of the display device, adapted to illuminate the forward face of the housing.

Signed at Chicago, county of Cook and State of Illinois, this 25th day of November, 1930.

ROBERT E. SPIEL.
